UNITED STATES PATENT OFFICE.

CHARLES G. DEVINE, OF DORCHESTER, MASSACHUSETTS.

FOOTBALL GAME.

Application filed May 17, 1926, Serial No. 109,778. Renewed May 24, 1927.

This invention relates to a game of skill and strategy and more particularly to such a game having the elements and principles of football.

5 It is an object of the invention to produce a game board having the representation of a regulation football field thereon, and having a plurality of objects representing players adapted to be arranged in team formation for offensive and defensive purposes.

10 It is a further object of the invention to produce a game wherein skill and strategy are the dominating factors and wherein but a small percentage of the plays are decided 15 by chance.

Another object of the invention is to produce a miniature football game wherein the players of one team are easily distinguished from those of the other team, and wherein 20 each player has a distinguishing mark designating his position on his respective team.

It is a further object of the invention to produce a game board wherein the playing field is divided into squares and wherein 25 each square has a hole therein for the reception of a pin with which each of the players is provided for the purpose of positioning the players about the board for various team formations and individual moves of the 30 players.

Heretofore in football games of this class known to me, the exercise of skill and strategy was not required because of the fact that the movement of the ball was decided by chance plays directed by an indicator which 35 was operated by the participants in turn, and players were not used which could be moved individually for strategic purposes, consequently the games were uninteresting 40 and not instructive.

The present invention contemplates a game wherein both skill and strategy are necessary factors for the successful termination of a game and wherein a knowledge of the 45 game of football though not necessarily required, when combined with skill and strategy in choosing the player to carry the ball, and in moving the players to protect that player, and to break the opponents' line adds 50 enthusiastic interest to the game which cannot be aroused in the mere games of chance heretofore known to me.

The invention will be fully understood

from a description of the drawings and the claim hereinafter given.

Of the drawings—

Figure 1 represents a top plan view of the game board upon which a miniature football field is indicated with the players arranged as might be the case at the start of the game or kick-off.

Figure 2 is a side elevation of the game board shown in Figure 1.

Figure 3 is an enlarged view of a portion of the game board showing a possible formation at the start of a scrimmage.

Figure 4 is an enlarged view of one of the indicators to be used for certain of the plays.

Figure 5 is an enlarged view of one of the 70 objects representing a player carrying the ball.

Figure 6 is a top plan view of Figure 5 showing a portion of the game board with 75 one of the objects representing a player thereon as carrying the ball, and exposing to view the distinguishing mark which designates his position on his team.

Like characters represent like parts throughout the several figures of the drawings.

Referring to the drawings.

The drawings herewith illustrate a simple means of applying the invention wherein a board 10 of any suitable material has a representation of a football field arranged thereon having the usual goals and ten-yard lines prominently displayed.

For the purpose of the present game the field is divided into squares in the middle of each of which is a hole 11 for the reception of a pin 12 with which each of the objects 13, representing the players, is provided, the said squares being preferably considered to be one yard square.

Each of the players 13 is provided with means 14 to which the ball 15 may be attached as shown in Figure 5 of the drawings.

For convenience of explanation the objects 13 will be hereinafter referred to as players 100 while the supposed persons making the moves or plays will be referred to as A and B.

At preferably diametrically opposite corners of the board 10 are located the indicator 105 devices 16 which are brought into use at the

start of the game and at such times as plays are called for or decided upon that cannot be actually performed by the players as will be further described.

5 The contesting teams will consist of the regulation number, or eleven players each, and to avoid confusion the players of one team will bear a color distinguishing it from the players of the other team but not shown herein, as for instance crimson for Harvard and blue for Yale, and each player will have a mark or character designating his position in the formation of his team, as for instance the center will have the numeral 1 while the 10 right guard, right tackle, right end, quarter-back and right half-back will have the numerals 2, 4, 6, 8 and 10 respectively, the 15 left guard, left tackle, left end, left half-back and full-back will have the numerals 3, 5, 7, 9 and 11 respectively.

20 The players of the other team will be similarly numbered but herein they will be referred to as numbers 1^x to 11^x inclusive to avoid confusion in the explanation of the 25 different plays.

20 The indicators 16 are each provided with an arrow 20 arranged to be spun by one or the other of the contestants A or B at the start of the game for a chance indication of the 30 number of yards gained by the kick-off as represented by the figures in the outer circular area, the next inner area contains figures which represent the yardage gained by the side receiving the ball after the kick-off, after a punt, or after the interception of a forward pass.

40 The success or failure of a forward pass is indicated on the next inner area, while the success or failure of a try for goal from the field, the try for goal after touchdown, or a drop kick is indicated on the innermost circular area.

45 In playing the game the official rules of football will be observed as far as possible, and the participants will toss up for choice of team, goal and kick-off.

50 Viewing Figure 1 let it be supposed that A has won the toss and has chosen his team, goal, and elected to kick-off, and thereupon lines up his players at the left of the board for that purpose, and therefore his team becomes the offensive one.

55 Generally speaking, ground gaining by the offensive team by plunges, end runs, and line breaking is somewhat slow in progress and consequently for the purpose of the present game the players on that team are somewhat restricted as regards the amount of yardage they are permitted to advance on 60 each move.

The four back field players consisting of the quarter-back, left half-back, right half-back, full-back and the two ends, or numbers 8, 9, 10, 11, 6 and 7 may be moved from one to four squares in any direction excepting

backward at the discretion of the participant A, while the five line men 1, 2, 3, 4 and 5 may move either one or two squares ahead or at an angle to the line of scrimmage but not sidewise or backward.

70 The defensive team under the guidance of B may be formed or spread over the field according to the ideas or strategy B has in mind but his players have more freedom for forward movement as his four back field 75 players and ends may each move from one to six squares in any direction excepting backward, their numbers being respectively 8^x, 9^x, 10^x, 11^x, 6^x and 7^x, while the five line men 80 may be moved from one to three squares forward or at an angle to the line of scrimmage but not backward, their numbers being 1^x to 5^x inclusive.

85 When both teams are arranged on the field as shown in Figure 1 of the drawings, A will kick-off to start the game by spinning the arrow 20 on his end of the board to determine by chance the distance the ball shall be advanced toward B's goal which might be 90 from ten to sixty yards.

90 Let it be supposed that the kick-off resulted in advancing the ball to B's twenty-yard line and supposedly in a straight line down the field and that the nearest player to the ball is 10^x, B will move 10^x to the position 95 the ball is supposed to occupy and will attach the ball to that player.

95 B will now spin the arrow 20 on his indicator to determine by chance the distance 10^x is supposed to return the ball by a run 100 which we will say is 12 yards as shown by the resting place of the arrow and the numeral to which it points in the circular area having 12 as the highest numeral thereon.

100 The ball will be removed from 10^x and 105 will now be placed in a square at B's thirty-two yard line, and the teams formed for 110 scrimmage as shown in said Figure 2.

110 The ball being in the possession of B's team, it is now B's first move and his players 115 must be moved in accordance with the limitations above referred to for the offensive team.

115 If B decides to snap the ball back to a particular player he will do so by attaching the ball to that player; he will then move that player or any other player in his discretion, the number of squares required or allowed as best suits his purpose and object he has in mind.

120 Each participant in turn moves a player, the object being for the offence to advance the ball for gains or a touchdown as in the usual game and for the defence to prevent the advance, and obtain the ball on downs.

125 If a player of the defensive team succeeds in getting so close to the player carrying the ball and by his next move would occupy the same square, such play counts as a down, and in case a player of a team is 130

40

blocking the progress of the ball and he is to be disposed of a player of the other team may if possible maneuver so as to finally on his next move occupy the same square when both of those players will be taken off the board until the next lineup or formation for scrimmage.

It is not deemed necessary to enumerate the many plays and combinations possible, as it is believed that it will be understood that the game is one requiring skill and strategy for success and that a knowledge of football is not necessary but very beneficial.

15 In the event that a touchdown is made the participant directing that team resorts to the indicator 16, spins the arrow 20 and abides by the result of the decision as "good" or "not good," whereupon play will 20 be again resumed according to the official rules of the game of football.

As in the regular game linesmen L are provided at the sides of the board for the usual purpose.

23 From the foregoing it will be readily understood that the great majority of the moves of the players are made by the participants and to great extent the result of the game depends upon the skillful manner 20 in which the moves are made and the strategy exercised in planning the attack or defense as the case may be.

It is not known that a football game of this class has ever been made wherein players have been used, and arranged to be moved individually for formation or strategy, or wherein a ball is used and arranged to be carried by any one of the players chosen for the purpose, or wherein the great

majority of the plays are made by the participants without the help or aid of indicators manually operated, and which merely indicate chance decisions and not the exhibition of skill or strategy.

Having described the invention I claim: 45

A game of foot ball requiring an element of skill and chance decisions, and comprising a board laid out in representation of a foot ball field, and having its playing surface further divided into areas each representing one yard square, each area being provided with a hole centrally thereof; objects representing players to the number required for two opposing teams, each player being provided with a pin extending 55 from the base thereof for engagement with the holes of the said board whereby the said players may be temporarily, and removably fixed in the said areas in any line up or formation desired, each player being 60 provided with a hook for the temporary attachment of a ball thereto; an object representing a ball provided with an eye to engage the hook of any designated player; an indicator device at each end of said board 65 one arranged to be manipulated to indicate a chance decision at the start of the game, as for a kick off by the offensive team, and the other to be manipulated by the defense to give a chance decision as to the yardage 70 gained on a supposed run back; said ball being arranged to be removed from a player of the offensive team carrying it at the time of kick off, to a player designated to make 75 the supposed run back.

Signed by me at Boston, Massachusetts, this 11th day of May 1926.

CHARLES G. DEVINE.
